UNITED STATES PATENT OFFICE.

WILLIAM SCHÓNHEYDER, OF SHEPHERDS BUSH, LONDON, ENGLAND.

DEVICE FOR FASTENING DRAWING-PAPER TO DRAWING-BOARDS.

SPECIFICATION forming part of Letters Patent No. 284,334, dated September 4, 1883.

Application filed February 9, 1883. (No model.)

To all whom it may concern:

Be it known that I, WILLIAM SCHÓNHEYDER, a native of Denmark, residing at Shepherds Bush, London, England, have invented 5 a new and useful Device for Fastening Drawing-Paper to Drawing-Boards, or for other similar purposes, such as securing thin metal plates to boards.

The following is a specification of my invention.

The object of my invention is to enable a sheet of paper to be secured to a drawing-board without the use of the usual pins, and thus to avoid puncturing it, while facilitating holding 15 it to and releasing it from the board, and, furthermore, to enable a sheet to be replaced upon the board in the same position with relation to the board that it occupied previous to its removal therefrom. I attain these objects by 20 the mechanism illustrated in the accompanying drawings, in which—

Figure 1 is a plan view of one corner of a drawing-board with my device inserted in the board. Fig. 2 is a view from point D, Fig. 1, 25 with the drawing-board shown in section. Fig. 3 is a view on the line D' D in Fig. 1, the drawing-board being shown in section. Fig. 4 is a view of the clip separated from all the other parts, and Fig. 5 is a top and edge 30 view of the spring.

Similar letters refer to similar parts throughout the several views.

The drawing-board is recessed at the corner to admit the clip C and the corner of the drawing-paper, and it is also recessed at the bottom or underneath side to receive the spring g and give room for its motion. Clip C is provided with two legs, e, which pass through holes in the drawing-board. Each of the legs 35 e is provided with two slots, f, through which

the ends of the spring g pass, these ends also being provided with a slot. The spring g abuts against the drawing-board at h, the recess in the board being shallow at h and deepened toward each end to give room for the motion of the spring. The tension of the spring 45 obviously pulls the clip C down into its recess in the board, and causes it to grip the corner of the drawing-paper S, which is inserted under the clip. By pressing the plate P with 50 the fingers the clip C is raised against the pressure of spring g, and the paper is released and may be removed. The operation therefore is to press the plate P upward with the fingers, thus raising clip C to admit the paper, and upon 55 releasing P from the finger-pressure cap G is pulled down upon the paper S by the force of spring g. To enable the sheet of paper to be reinserted and set in the same position after having been removed, a line, l, is marked on 60 the face of C, a coincident line being marked on the sheet of paper.

Having thus described my invention, what I claim as new, and desire to secure by Letters Patent, is—

1. In a drawing-board, the clip C, having two or more legs or projections, e, adapted to receive the pressure of a spring or springs, g, substantially as and for the purpose specified.
2. The clip C, having projections e, provided with slots f, in combination with a spring, g, and plate P, substantially as and for the purpose set forth.

W. SCHÓNHEYDER.
